UNITED STATES PATENT OFFICE.

ELI EDWARD GREGORY, OF CENTRAL CITY, KENTUCKY.

WATER, LAND, AND AIR MACHINE.

1,094,989.

Specification of Letters Patent. Patented Apr. 28, 1914.

Application filed November 4, 1913. Serial No. 799,216.

To all whom it may concern:

Be it known that I, ELI E. GREGORY, a citizen of the United States, and a resident of Central City, in the county of Muhlenberg and State of Kentucky, have made certain new and useful Improvements in Water, Land, and Air Machines, of which the following is a specification.

My invention relates to improvements in hydroplanes which are also adapted to run on land, and it consists in the combinations, constructions, and arrangements herein described and claimed.

An object of my invention is to provide a device which is so constructed that it may be used as an aeroplane, as a boat, or a land vehicle without any change in the device when going from one element to the other.

A further object of my invention is to provide a device of the type described having novel means for directing the course of the device.

A further object of my invention is to provide a novel form of hull for use on the water which serves as the main sustaining plane when used in air.

Other objects and advantages will appear in the following specification and the novel features of the device will be particularly pointed out in the appended claims.

My invention is illustrated in the accompanying drawings forming part of this application in which—

Figure 1 is a central vertical section through the device, Fig. 2 is a section along the line 2—2 of Fig. 1, Fig. 3 is a section along the line 3—3 of Fig. 1, Fig. 4 is a plan view of the device, Fig. 5 is a section along the line 5—5 of Fig. 1, and Fig. 6 is a plan view of a portion of the steering apparatus.

In carrying out my invention I provide a central longitudinal frame member 1 extending from end to end of the machine. At substantially one-fourth of the member 1 from one end I arrange a triangular frame composed of the horizontal cross member 2 (see Fig. 2) and the inclined members 3. Cables 4 are secured to the front and rear ends of the main longitudinal frame member 1 and to the three points formed by the triangular frame which is composed of the members 2 and 3. The hull is completed by stretching flexible material such as that shown at 5 over the frame work thus formed. This may be done in a variety of ways. I prefer to make use of wire netting on which

canvas is sewed, after which it is treated with waterproofing material thus forming a strong, waterproof, flexible member 5 which is light, but which is sufficiently strong to serve as a sustaining plane when in air or as the body portion of the hull when the device is to be used in water.

Secured at the junction of the members 3 (see Fig. 2) is a thrust bearing 6 upon which is mounted a vertical post 7, the latter passing through the longitudinal members 1 and also through the horizontal member 2. This post supports a rigid cross rod 8 to which is pivotally secured by means of rings 9 which encircle the arm 8 a light bar 10 of substantially the same length as the bar 8. Carried by the bar 10 is the forward elevating plane 11 which is constructed in a manner similar to the construction of the hull. It will be observed that this plane 11 is curved from front to rear as shown in Fig. 1. It bears a central fin 12 which projects upwardly as shown in Fig. 2.

Near the rear end of the machine is a vertically extending post 13 which is mounted on the main frame 1, as shown in Fig. 3. The lower end of this post is provided with a fork 14 which supports a wheel 15. The upper end carries a cross bar or rod 16 to which is pivotally connected by means of rings 17 a bar 18 which bears the rear controlling plane 19. This plane 19, as will be seen from Fig. 1, is also provided with a central fin 20 constructed of similar material to the front elevating plane 11 and the hull.

The motor is disposed near the front part of the machine, as shown at M. The shaft of the motor 21 extends rearwardly and is connected by a belt 22 with a shaft 23 which bears the propeller 24. The shaft 23 is mounted on a frame 25, which is carried by a cross member 26 (see Fig. 5).

For controlling the side movement of the device I provide a steering wheel 27 upon whose spindle are the drums 28 which control the wires 29 leading to the quadrant 30, the latter being secured to the post 7 so that when the steering wheel is turned the post will be rotated on its longitudinal axis, thereby turning the front plate to the right or left, so that the fin 12 acts as a guide member. Rearwardly extending cords 31 (see Fig. 4) connect with the ends of the front quadrant 30 and are secured to a rear quadrant 32. These wires 31 are crossed,

thereby turning the rear vertical post 13 in the opposite direction from the front vertical post 7, thus turning the rear fin 20 simultaneously and in the opposite direction 5 to the front fin 12.

The means for guiding the device in its up and down movement consists of a drum 33 mounted on a shaft 34 (see Figs. 4 and 6) to which an operating lever 35 is secured. 10 Cords 36 pass rearwardly from the drums being secured to the forward and rear planes on each side of their pivots in such a manner that when the hand lever is moved in one direction the front end of the front plane 15 is tipped downwardly while the front end of the rear plane is tipped upwardly. When the lever is moved in the opposite direction the reverse movement of the two planes takes place.

20 In order to provide for use on land front wheels 37 are provided, the axle 38 being carried by telescopic members 39 which are provided with springs 40 to resist the shock of impact when the machine descends.

25 The rear wheel 15, as has been before stated, is mounted on the same spindle or rod 13 which bears the rear rudder or fin 20. Therefore when the steering wheel 27 is turned the rear wheel acts as a steering member without the necessity of any additional steering mechanism, thus the machine may be guided on land as well as in air. Furthermore by covering the space within the rim of the rear wheel with fabric or 30 other suitable material the rear wheel can be made to serve as a rudder when the device is to be used as a boat.

It will be seen that I have provided a device having a great range of capabilities. 40 The peculiar shape of the body portion renders it particularly adaptable for use both in water and in air, so that it will float readily when in water and will be buoyed up by the pressure of the air when used as 45 an aeroplane.

I claim:—

1. In a combined water, land, and air machine, a central longitudinal frame member, a triangular frame portion disposed near 50 one end of said longitudinal frame member, cables connecting the front and rear ends of said longitudinal frame member with the three angles of said triangular frame member, a flexible waterproof fabric extending 55 from the front end of the longitudinal frame member rearwardly underneath the triangular shaped frame portion and being connected to the rear end of said longitudinal frame member.

60 2. In a combined water, land, and air ma-

chine, a hull having a body portion of waterproof fabric, a front supporting post and a rear supporting post, each of said posts being mounted for revolution about their axes, a guide plane carried by each of said supporting posts, each of said guide planes having a body portion normally at right angles to its supporting post and pivoted thereto, and a vertically extending fin disposed centrally of said portion. 65

3. In a combined water, land, and air machine, a hull having a body portion of waterproof fabric, a front supporting post and a rear supporting post, each of said posts being mounted for revolution about their axes, 70 a guide plane carried by each of said supporting posts, each of said guide planes having a body portion normally at right angles to its supporting post and pivoted thereto, a vertically extending fin disposed centrally of said portion, and means for rotating said supporting posts simultaneously and in opposite directions. 75

4. In a combined water, land, and air machine, a hull having a body portion of 80 waterproof fabric, a front supporting post and a rear supporting post, each of said posts being mounted for revolution about their axes, a guide plane carried by each of 85 said supporting posts, each of said guide planes having a body portion normally at right angles to its supporting post and pivoted thereto, a vertically extending fin disposed centrally of said portion, means for rotating said supporting posts simultaneously and in opposite directions, 90 a pair of front supporting wheels carried by said hull, and a rear supporting wheel carried by said rear supporting post and movable there-with for supporting the device on land. 95

5. In a combined water, land, and air machine, a hull having a body portion of waterproof fabric, a front supporting post and a rear supporting post, each of said posts being mounted for revolution about 100 their axes, a guide plane carried by each of said supporting posts, each of said guide planes having a body portion normally at right angles to its supporting post and pivoted thereto, a vertically extending fin disposed centrally of said portion, means for 105 rotating said supporting posts simultaneously and in opposite directions, and means for simultaneously tilting the front and rear guide planes in opposite directions. 110

ELI EDWARD GREGORY.
